YORK, A CORPORATION OF NEW YORK.

ABSOLUTE PERMISSIVE AUTOMATIC BLOCK-SIGNAL SYSTEM.

1,292,965.

Specification of Letters Patent. Patented Jan. 28, 1919.

Original application filed February 7, 1911, Serial No. 607,098. Divided and this application filed December 27, 1915, Serial No. 68,786. Renewed April 15, 1918. Serial No. 228,807.

To all whom it may concern:

Be it known that we, WILMER W. SALMON and FRANK L. DODGSON, citizens of the United States, and residents of New Ro- 5 chelle and the city of Rochester, in the county of Monroe and State of New York, have invented a new and useful Absolute Permissive Automatic Block-Signal System, of which the following is a specification.

10 This invention relates to automatic block signal systems and is especially adapted for use on single track railways. The object of the invention is to provide a signaling system adapted to be operated by the ordinary closed track circuits commonly used in automatic block signaling systems and adapted to secure head-on protection from passing siding to passing siding, with blocks for following train moves as short as track 15 conditions require.

So far as known to us prior to our invention, a greater part, if not all of the single track railroads in use have employed the ordinary automatic block signal system in 20 which a train entering the block from either direction gives the same indication and thus has the same protection for following trains as for head-on trains. Many attempts have been made to attain the results attained by 25 our invention, but, so far as known to us, none of the systems proposed were adapted to be operated by the ordinary closed track circuits in common use on railways, and all of them involved using additional and complicated apparatus or circuits, and making 30 the operation of the signals for following movements more or less dependent upon the operation of signals governing head-on movements.

40 Primarily, the invention may be termed a unit system in that our means are adapted to be located at and operated by any track circuit controlling a signal governing traffic in one direction without regard to signals 45 governing the traffic in the opposite direction; but it will be understood, of course, that in the practical embodiment of our invention the usual signals governing head-on protection are employed.

50 In carrying out our invention, we preferably employ a signal circuit adapted to be opened by a train on the track circuit sections of a block and a further signal circuit

adapted to be closed only by a train which enters the block from one direction, both of 55 these circuits being operated by the ordinary closed track circuit sections in common use on railroads.

This application is a division of our prior 60 application, Serial No. 607,098, filed February 7, 1911.

This invention will be more fully described hereinafter with reference to the form thereof herein illustrated and which we have selected as an example for the 65 purpose of explaining the principles involved, it being understood that the invention may be embodied in various forms and arrangements of apparatus.

In the accompanying drawings, the figure 70 illustrates diagrammatically the circuits and apparatus of one embodiment of our invention applied to a railway.

Construction.—Referring to the drawing, 1, 2 and 3 designate track circuit sections, 75 separated by means of insulating joints 4; 1¹, 2¹ and 3¹ designate track batteries for creating a difference of potential between the two rails of the track; 1², 2² and 3² designate relay coils normally energized by current flowing therethrough due to the difference of potential created by the track batteries; 1³ designates a relay armature held normally in the upper position as shown by reason of the current flowing in relay 80 coil 1²; 2³, 2⁴ and 2⁵ likewise designate armatures normally in the upper position shown by reason of current in relay coil 2²; 3³ likewise designates the armature of relay coil 3² normally held in the upper position; 90 5 designates a semaphore as does likewise 6; 5¹ and 6¹ designate the electric motors for moving semaphores 5 and 6 respectively; 5² and 6² designate the "hold clear" devices for holding the semaphores 5 and 6 respectively 95 in their moved position; 5³ and 5⁴ designate metallic arms moved in unison with semaphore 5 and designed to at times make contact with metallic strips 5⁵, 5⁷, 5⁸ and 5⁶, the arm 5³ making contact with metallic strip 100 5⁵ at the 45° position of the semaphore and for a few degrees on either side of such 45° position, the arm 5⁴ making contact with metallic strip 5⁶ at the zero or danger position of the semaphore and during the whole 105 movement of the semaphore except the last

- few degrees; the arm 5³ making contact with the metallic strip 5⁷ at the full clear or 90° position of the semaphore 5 and for a few degrees on either side of such 90° position, 5 the arm 5⁴ making contact with the metallic strip 5⁸ during the movement of the semaphore 5 from just below the 45° position almost to the full clear or 90° position; 6³, 6⁴ and 6⁵ designate metallic arms moved in 10 unison with semaphore 6, the arm 6³ designed to make contact with metallic strip 6⁶ at the 45° position of the semaphore and for a few degrees on either side of said 45° position, 6⁴ making contact with metallic 15 strip 6⁷ at the zero or danger position of the semaphore and during the whole movement of the semaphore except the last few degrees, 6⁵ not making contact at the zero or danger position of the semaphore with metallic strip 6⁸ but making contact therewith as soon as the semaphore has moved a few degrees and remaining in contact therewith during the whole of the remainder of the movement of the semaphore; 8 designates a 20 relay coil which when current passes therethrough causes armature 8¹ to be held in its upper position; 7 designates a relay coil which when a current of sufficient value passes therethrough will draw armature 7¹ 25 to the upper limit of its movement; 9 designates a resistance which is of such value that it will allow sufficient current to pass therethrough to sufficiently energize coil 7 so that it will hold armature 7¹ in its upper 30 position if already there but will not allow sufficient current to pass therethrough to sufficiently energize coil 7 so that it will move armature 7¹ to its upper position, if it is in its lower position.
- 40 *Operation.*—In the normal condition of the connections, relay 8 is energized by current in the following circuit: positive terminal of battery 17, wire 19, relay armature 3³, wire 20, relay armature 2³, wire 21, relay 45 coil 8, wires 22, 23, 24 and 25 to the negative terminal of battery 17; the relay coil being thus energized the armature 8¹ is normally held in its upper position.
- If a train moving in the direction of the 50 arrow *a* comes upon section 1, it will shunt the relay 1² thereby dropping the armature 1³ so that it makes connection with its back contact, thereby establishing the following circuit: positive terminal of battery 10, wires 55 26 and 27, armature 8¹, wires 28 and 29, metallic strip 6⁷, arm 6⁴, wire 30, motor 6¹, wires 31, 32 and 33, relay armature 1³, wires 34 and 24 to the negative terminal of battery 10. The current flowing in such path 60 will cause the motor to operate to move the semaphore 6 to the 45° or clear position causing the arm 6⁴ to move over metallic strip 6⁷ until the semaphore almost reaches the 45° position when arm 6⁴ will break contact with strip 6⁷ thus stopping the motor,

but at the 45° position of the semaphore 6 the arm 6³ will make contact with metallic strip 6⁶ so that the current which formerly flowed through the motor will now flow through the hold clear device from the wire 70 28 by the following path: wire 28, wire 35, strip 6⁶, arm 6³, wire 36, holding coil 6², wire 37 to wire 33 and so by the before traced path to the negative terminal of the battery. The current flowing in such last 75 traced path will cause the semaphore to be held in its 45° or clear position, as soon however as the train which entered section 1, enters section 2, the relay coil 2² will be shunted, the armature 2³ will break contact with wire 20 and therefore the current through relay coil 8 will cease causing armature 8¹ to fall stopping the flow of current through the holding coil, which consequently permits the semaphore 6 to fall to 80 the zero or danger position to protect the train. The semaphore 6 will remain at danger and cannot be moved to the 45° position so long as a train is on section 2 or 3 for under such conditions the energizing circuit for relay coil 8 is broken either by the dropping of armature 2³ or armature 3³ depending on whether a train is on section 2 or 3. As soon, however, as the train which 85 passed signal 6 passes the end of track section 3 the relay 8 will again become energized, relay armature 8¹ will be lifted and the system would then be in condition to be again operated as before.

When a train enters section 2 traveling 100 in the direction of the arrow *a* the semaphore 6 is, at that instant, in the 45° or clear position so that arm 6⁵ makes contact with strip 6⁸ and as by the entrance of the train on section 2 the armatures 8¹ and 2³ are allowed to fall for reasons heretofore explained, a circuit is formed as follows: positive terminal of battery 10, wires 26, 44 and 38, arm 6⁵, strip 6⁸, wire 39, armature 2³, wires 40 and 41, relay coil 7, wires 42, 23 110 and 24 to the negative terminal of battery 10. The current flowing in the above mentioned circuit sufficiently energizes coil 7, so that it lifts armature 7¹, thereby rendering effective another circuit as follows: positive 115 terminal of battery 10, wires 26 and 27, armature 8¹, wire 43, resistance 9, wire 41, relay coil 7, wires 42, 23 and 24 to the negative terminal of the battery. The current flowing in this last traced circuit it will be 120 observed does not depend upon the position of semaphore 6 for its continuity, but due to the resistance 9 of the current flowing is only sufficient to hold the armature 7¹ in its upper position, but is not sufficient to raise 125 the armature if it is down, it being necessary to have a circuit made through arm 6⁵ and strip 6⁸ to cause sufficient current to flow through relay coil 7 to raise armature 7¹, so that after 7¹ has once been raised by the en- 130

trance of a train upon section 2 traveling in the direction of the arrow *a*, it will remain in its upper position during the time the said train is on either sections 2 or 3, 5 but will fall to its lower position as soon as the train leaves section 3, as the relay coil 8 will then lift armature 8¹ and break the circuit through coil 7.

If a second train should approach traveling in the direction of the arrow *a* before the first train had left sections 2 or 3 so that armature 7¹ was still in its upper position, upon entering section 1, it would shunt relay coil 1² and cause armature 1³ to drop thus 10 closing the following circuit: positive terminal of battery 10, wires 26, 44 and 45, armature 7¹, wire 46, strip 5⁶, arm 5⁴, wire 47, motor 5¹, wires 48, 49, 50, 32 and 33, armature 1³, wires 34 and 24 to the negative 15 terminal of battery 10. The current in said circuit would operate the motor 5¹ to move the semaphore 5 to the 45° position at which point arm 5⁴ would break contact with strip 5⁶ thus cutting off the current from the motor, but at the same time the current which 20 was flowing through the motor would be directed through the hold clear device 5² flowing from wire 46 to wire 51, strip 5⁵, arm 5³, wire 52, holding coil 5², wire 53 to wire 50 25 and to the negative terminal of the battery as before, thus holding the semaphore in its 45° position. It is to be observed that the 30 said second train would not be able to clear semaphore 6 if a train were in either sections 2 or 3 for the very presence of a train on either of said sections deenergizes relay 35 8, thus causing armature 8¹ to be in its lower position, thus breaking the operating circuit for semaphore 6.

40 When the second train passes semaphore 5 it goes to the zero or danger position due to the fact that armature 1³ is drawn to its upper position, but all other parts of the system remain as before so that a 45 third train approaching in the direction of arrow *a* would be able to operate semaphore 5 to its 45° position and so enter section 2. It will be thus seen that sections 2 and 3 could be filled with trains 50 all going in one direction; but a train approaching section 2 in the direction of arrow *a* could not operate semaphore 6 until the last train had left section 3, for just so long as there is a train on section 55 2 or 3 relay armature 8¹ would be down, thus preventing the operation of semaphore 6.

It is also to be observed that as soon as the last train left section 3, the next train 60 approaching in the direction of arrow *a* would not be able to operate the semaphore 5 for by the exit of the preceding train from section 3 relay coil 8 would be energized and armature 8¹ lifted breaking circuit through coil 7 which would cause 65

armature 7¹ to drop preventing the operating circuit of semaphore 5 from being closed by the entrance of a train on section 1.

If a train should enter section 3 traveling in the direction of arrow *b* it would prevent all operation of the signals 5 and 6 by the subsequent entrance of a train on section 1 moving in the direction of arrow *a*, for the first said train would shunt relay 7² thus causing armature 3³ to drop and break the energizing circuit of relay 8, which would cause armature 8¹ to fall and prevent the clearing of semaphore 6 when the said subsequent train entered section 1. The dropping of relay armature 8¹ would not however cause relay 7 to be energized by the circuit heretofore described for resistance 9 would not allow sufficient current to flow through relay coil 7 to energize it sufficiently to lift armature 7¹ consequently the operating circuit of semaphore 5 would be broken; which condition would exist as long as the first said train remained on sections 2 or 3. 90

Those skilled in the art of railway signaling and especially single track automatic block signaling can readily understand that the system above described accomplishes a result not before attained 95 but long sought, for by its use all of the advantages of a signal system employing track circuits are preserved, the advantages of an automatic system are preserved and at the same time the added result of being able to govern semaphores 5 and 6 in accordance with the presence and direction of movement of a train on a track circuit section is attained. 100

The semaphore 5 is caused to have different aspects according to whether a train which has passed semaphore 5 going in the direction of arrow *a* is in section 2 or section 3. This is accomplished by giving to semaphore 5 three positions so that when 110 a train is on section 2, semaphore 5 could be moved to the 45° position, but when the train is on section 3 it could be moved to the 90° position.

A train approaching semaphore 5 and 6 115 from the direction of the arrow *a* will first enter upon section 1; and if no train is on sections 2 or 3 semaphore 6 will be moved to the 45° position allowing the train to proceed at full speed past the signal and if a train was on either sections 2 or 3 and had entered upon sections 2 or 3 from the direction of the arrow *b*, the train approaching from the direction of the arrow *a* would receive no proceed signal at all. If, however, a train approached in the direction of arrow *a* while a preceding train was on section 2, the semaphore arm 6 would not be moved but the semaphore arm 5 would move to the 45° position. 125 130

tion. In order to differentiate the condition of the presence of a train in section 2 from that when a train is in section 3, the semaphore 5 would move to the 90° position if a train approached in the direction of the arrow *a* while a preceding train was on section 3, the circuit for such a movement when relay armature 7¹ is in its upper position due to the passing of 5 a train in the direction of arrow *a* beyond the semaphores 5 and 6 being as follows: positive side of battery 10, wires 26, 44, 45, armature 7¹, wires 46, 71, armature 2⁴, wires 74 and 75, metallic strip 5⁸, arm 5⁴, 10 wire 47, motor 5¹, wires 48, 49, 50, 32, 33, armature 1³, wires 34 and 24 to the negative terminal of the battery 10. The current flowing in the above traced path would cause the motor to operate and move 15 the semaphore 5 to its 90° position, it, of course, being moved previously by the same circuit hereinbefore described to the 45° position and after it has been moved by current in this last traced path to the 20 90° position, the current would then pass by wire 76 to metallic strip 5⁷, arm 5³ and wire 52 to the hold clear coil 5², and thence to the negative terminal of the battery by wire 53 as in the case when the motor was 25 30 being operated.

It will thus be understood that a train approaching semaphores 5 and 6 in the direction of the arrow *a* will be given a distinctive aspect due to the presence of a train on 35 either sections 2 or 3.

Although applicants have selected the well known normal danger system of operating signals in connection with the embodiment of their invention which they have 40 selected to illustrate the principle of their invention, it is to be distinctly understood that it is immaterial whether the so-called normal danger system of signaling is employed in connection with this invention or 45 whether the so-called normal clear system is employed for, to transpose from the normal danger system to the normal clear system would simply mean the absence of the preliminary clearing section 1, shown in 50 each of the figures and in place thereof; the substitution of the conductor shown by dotted line 77. It is furthermore to be observed that the aspects of the signals would either 55 with the normal danger or the normal clear systems be identical and that under the same conditions as regards the presence of a train which has passed the semaphores 5 and 6, the aspects of the signal displayed to an 60 approaching train would in the two systems be identical.

In practice the system shown would be duplicated for single track, the opposing semaphores corresponding to semaphores 5 and 6 being in the well known manner interlocked electrically, that is, 5 and 6 at one

end of the block with 5 and 6 at the other end and all would be controlled by the same track circuit sections, so that a train approaching a semaphore in either direction would, if semaphore 6 moved to the clear 70 position, enter the block controlled thereby at full speed. If the arm 5 moved to the 45° position, the train would enter the block under control. If neither semaphore assumed the 45° position the approaching 75 train would not enter the block.

Although we have herein shown and described the relay 7 as governing a semaphore 5 it is to be understood that such are only single instances of an exhibition of its functions. In its broadest aspect the principle of relay 7 may be employed in controlling one or more aspects of any semaphore, located at any point, having a plurality of aspects, when such semaphore should have 80 some one or more of its aspects controlled by the presence and direction of movement of a train on the track circuit sections controlling relay 7, and it is immaterial whether or not such semaphore is also jointly controlled in 85 its aspects by other means, and therefore we desire it to be understood that such applications being well within the skill of those learned in the art of railway signaling would embody the principle of the idea of 90 means herein set forth.

Having particularly described the construction and operation of physical embodiments of our invention and explained the operation and principle thereof, what we 100 claim as new and desire to protect by Letters Patent is:

1. In a signaling system for railways, in combination: a stretch of track divided into track circuit sections; a circuit controller; means rendered effective if a portion of the track is occupied by a train and another portion is not occupied for closing said circuit controller; means capable of acting initially only when said first means is effective 105 for maintaining said first means effective so long as said other portion of the track is occupied; a circuit including said circuit controller; means for interrupting said circuit while said first mentioned portion of 110 the track is occupied; and means for signaling controlled by said circuit.

2. In a signaling system for railways, in combination: a first track circuit section and a second track circuit section; a device adapted to be governed electrically; a circuit for rendering said device effective controlled jointly by both of said track circuit sections and closed if the first track section but not the second track section is occupied by a 120 train; another circuit controlled jointly by said device and said first track circuit section, and closed if said device is effective and said first track section is unoccupied; means rendered capable of acting initially only 125 130

- when said device is effective for maintaining said device effective while said second track section is occupied; and means for signaling governed by said another circuit.
- 5 3. In a signaling system for railways, in combination: a track circuited track including a first track circuit section and a second track circuit section each having a track relay; an armature operated by the track relay of the first track section and in closed position when that section is occupied; a second circuit controller governed by the second section and opened when that section is occupied; a device adapted to be governed electrically; a circuit for energizing said device including in series said circuit controller and said armature; a circuit having a normally open break therein closed by said device when it is energized; means for interrupting said last mentioned circuit while said first track section is occupied; and means for signaling governed by said last mentioned circuit.
- 10 4. In a signaling system for railways, in combination: a track circuited track including a first track circuit section and a second track circuit section each having a track relay; an armature operated by the track relay of the first track section and closed when that track relay is deenergized; a circuit controller governed by the track relay of the second track section and opened when that track section is occupied; a device adapted to be governed electrically; a circuit for rendering said device effective including in series said armature and said circuit controller; means capable of acting initially only when said device is effective for maintaining said device effective while the second track circuit section is occupied; a circuit governed jointly by said device and the track relay of the first track section and closed only when said device is effective and the first track section is not occupied; and means for signaling governed by the last mentioned circuit.
- 15 5. In a signaling system for railways, in combination: a stretch of track divided into track circuit sections; a first semaphore and a second semaphore each having a stop aspect and a proceed aspect and governing traffic in the same direction, a circuit for controlling the first semaphore; means for interrupting said circuit when a predetermined portion of the track is occupied; a circuit controller subjected to the same controlling influence as the second semaphore and closed when that semaphore has its proceed aspect; another circuit controller governed by said predetermined portion of the track and closed when that portion of the track is occupied; and means which is controlled jointly by said circuit controllers and which is rendered effective when both of
- 20 6. In a signaling system for railways, in combination: a stretch of track divided into track circuit sections; a first semaphore and a second semaphore each having a stop aspect and a proceed aspect and governing traffic in the same direction, a circuit for controlling the first semaphore having its continuity determined at two separate places; means for breaking said circuit at one of said places when a portion of the track protected by the first semaphore is occupied; a translating device having coöperating contacts which maintain the continuity of said circuit at the other of said places when said translating device is energized; a circuit controller subjected to the same controlling influence as the second semaphore and closed when that semaphore assumes its proceed aspect; another circuit controller governed by the first mentioned portion of the track and closed when that portion is occupied; a circuit for energizing said translating device including said circuit controllers in series; and means for maintaining the coöperating contacts of said device closed until the second semaphore indicates proceed, said last mentioned means being initially dependent on the coöperating contacts of said device being concurrently closed.
- 25 7. In a signaling system for railways, in combination: a stretch of track divided into track circuit sections; a first semaphore and a second semaphore for governing traffic in the same direction over said track; a circuit controller subjected to the same controlling influence as the second semaphore and closed when that semaphore indicates that a predetermined portion of the track protected thereby is not occupied; a circuit for controlling said first semaphore having two places at which it may be broken, said circuit being opened at one of said places when a portion of the track protected by the first semaphore is occupied; means controlled jointly by said portion of the track protected by the first semaphore and by said circuit controller for closing said circuit at the other of said places, and means initially dependent upon said first mentioned means being concurrently effective for maintaining said first mentioned means effective to close said circuit as long as said portion of track protected by said second semaphore is occupied.
- 30 8. In a signaling system for railways, in combination: a stretch of track circuited track; a first semaphore and a second semaphore for governing traffic in the same direction over the track; a circuit for governing the first semaphore and for causing that semaphore to assume a proceed aspect when that circuit is closed, said circuit having two

- places at which it may be broken; means governed by a predetermined portion of the track protected by the first semaphore for interrupting said circuit at one of said places
- 5 when that portion of the track is occupied; a translating device which, when energized, establishes the continuity of said circuit at the other of said places; a circuit controller subjected to the same controlling influence
- 10 as the second semaphore and closed when that semaphore indicates that the portion of track protected thereby is not occupied; another circuit controller governed by the first mentioned predetermined portion of
- 15 the track and closed when that portion is occupied; a preliminary energizing circuit for said translating device including both of said circuit controllers in series; a maintaining circuit, including a source of current,
- 20 for maintaining said translating device energized and effective only when said energizing circuit is closed at the time said maintaining circuit is closed; and means for keeping said maintaining circuit closed
- 25 while the portion of track protected by the second semaphore is occupied.

9. In a signaling system for railways, in combination a stretch of track divided into track circuit sections; a semaphore having a proceed position and a stop position; a circuit controller governed by the semaphore and closed when said semaphore assumes its proceed position; a second circuit controller governed by a predetermined portion of the
- 30 track and closed when that portion is occupied; a device adapted to be governed electrically; a circuit for energizing said device including in series said circuit controllers; a circuit controlled by said device; means
- 35 for interrupting said last mentioned circuit when said predetermined portion of the track is occupied; and means for signaling governed by said last mentioned circuit.

10. In a signaling system for railways, in combination: a stretch of track divided into track circuit sections; a semaphore having a proceed position and a stop position; a circuit controller governed by the semaphore and closed when said semaphore assumes its
- 45 proceed position; a second circuit controller governed by a predetermined portion of the track and closed when that portion is occupied; a device adapted to be governed electrically; a circuit for rendering said device effective including in series said circuit controllers; a circuit controlled by said device; means for interrupting said last mentioned circuit when said predetermined portion of the track is occupied; means for signaling
- 50 governed by said last mentioned circuit; and means capable of acting initially only when said device is effective for maintaining said device effective so long as said semaphore remains in its stop position.

- 65 11. In a signaling system for railways, in

combination: a stretch of track divided into track circuit sections; two semaphores each having a proceed aspect and a stop aspect and governing traffic in the same direction over the track; a circuit for governing the first of said semaphores including two circuit controllers arranged in series, one of said circuit controllers being governed by a portion of the track protected by the first semaphore and being opened when that portion of the track is occupied; electrically operable means which, when energized, closes the other of said circuit controllers; a third circuit controller subjected to the same controlling influence as the second semaphore and being closed when that second semaphore assumes its proceed aspect and being opened when that semaphore assumes its stop aspect; a fourth circuit controller governed by said portion of the track protected by said first semaphore and closed when that portion of the track is occupied; an energizing circuit for said electrically operable means including a source of current and said third circuit controller and said fourth circuit controller in series; and means for maintaining the circuit controller governed by said electrically operable means closed as long as said second semaphore maintains its stop aspect, said last mentioned means being initially dependent upon said electrically operable means being concurrently effective.

12. In a signaling system for railways, in combination: a stretch of track divided into track circuit sections each having a track relay; a circuit; means controlled by the track relay of one of said track sections for interrupting said circuit; a circuit controller included in said circuit; means which, when supplied with current, closes said circuit controller; a circuit for supplying current to said means and having a normally open break and a normally closed break therein; an armature operated by the first mentioned track relay for closing the normally open break when that track relay is deenergized; and means controlled by the track relay of another track circuit section for opening said normally closed break when that track section is occupied.

13. In a signaling system for railways, in combination: a stretch of track including two track circuited portions; a semaphore for governing traffic over the track; a circuit for controlling said semaphore having its continuity determined at two places therein; means controlled by a portion of the track protected by said semaphore for interrupting said circuit at one of said places when that portion of the track is occupied; another semaphore for governing traffic in the same direction as the first semaphore; a circuit controller subjected to the same controlling influence as said other semi-

aphore and closed when that other semaphore indicates that a portion of the track protected thereby is not occupied; and means governed by said circuit controller and set 5 into operation by the movement of a train by said other semaphore in the direction of traffic governed thereby for closing said first mentioned circuit at the other of said places and for maintaining said first mentioned 10 circuit closed at said place until the train has left the portion of track protected by said other semaphore.

14. In a signaling system for railways, in combination: a stretch of track including 15 two separate track circuited portions; a semaphore for governing traffic over the track; a circuit for controlling the semaphore to cause it to assume its proceed aspect when energized; means controlled by a portion 20 of the track protected by the semaphore for interrupting said circuit; electrically operable means which, when ineffective, opens another break in said circuit; means for rendering said electrically operable 25 means effective; a second semaphore for governing traffic in the same direction as the first semaphore; means controlled by said second semaphore and rendered effective when that semaphore assumes its stop 30 aspect for preventing the energization of said electrically operable means; and means initially dependent upon said electrically operable means being concurrently effective for maintaining that means effective while 35 said second semaphore has its stop aspect.

15. In a signaling system for railways, in combination: a stretch of track divided into track circuit sections and including two contiguous portions; a circuit; means governed 40 by one of said portions of the track for interrupting said circuit when that portion is occupied; a translating device, which, when energized, closes said circuit if it is not interrupted by said means; a circuit controller 45 governed exclusively by the first mentioned portion of the track and closed when that portion is occupied; a circuit controller governed by the other portion of the track and open when that portion is occupied; a circuit 50 for energizing the translating device including in series both of said circuit controllers; and means for signaling controlled by said first mentioned circuit.

16. In a signaling system for railways, in 55 combination; a stretch of track divided into track circuit sections; a semaphore; a circuit for controlling said semaphore; means controlled by a track circuit section protected by the semaphore for interrupting 60 said circuit when that track section is occupied; electrically operable means which, when rendered effective, closes said circuit when the first mentioned means does not interrupt said circuit; two circuit controllers; 65 a circuit for rendering said electrically op-

erable means effective including said two circuit controllers only; one of said circuit controllers being governed by said first mentioned track circuit section and being closed when that track circuit section is occupied, 70 the other of said circuit controllers being governed by another track circuit section and being open when the latter track circuit section is occupied; and means capable of acting initially only when said electrically 75 operable means is effective for maintaining said electrically operable means effective so long as said another track circuit section is occupied.

17. In a signaling system for railways, in 80 combination: a stretch of track divided into track circuit sections and including two separate portions; a signal; a circuit for controlling said signal; means governed by one of said portions of the track for interrupting 85 said circuit when that portion is occupied; a translating device which, when energized, closes said circuit if it is not interrupted by said means; a circuit controller governed exclusively by said first mentioned 90 one of the portions of the track and closed when that portion is occupied; a second circuit controller governed by the other portion of the track and open when that portion of the track is occupied; and a circuit 95 for energizing said translating device including in series both of said circuit controllers.

18. In a signaling system for railways, in 100 combination: a stretch of track divided into track circuit sections and each having a track relay; a first circuit controller and a second circuit controller actuated simultaneously by the track relay of a predetermined 105 track circuit section and opened and closed respectively when that track section is occupied; a signal; a circuit for controlling said signal including the first circuit controller and having a normally open break therein; a device adapted to be governed electrically 110 and when energized closing said break in said circuit; an energizing circuit for said device including the second circuit controller; and means governed by the track relays of a portion of the track and initially 115 dependent upon the previous and also concurrent completion of said energizing circuit for maintaining said device energized.

19. In a signaling system for railways, in 120 combination: a stretch of track divided into track circuit sections; a signal; a circuit for governing said signal; a circuit controller included in said circuit; electrically operable means for operating the circuit controller; a circuit for controlling said electrically operable means, said circuit being controlled by the track circuit sections of a portion of the track and being open when that portion is occupied; and means governed by another 125 portion of the track for opening said first 130

- circuit and for closing said last-mentioned circuit simultaneously.
20. In a signal system for railways, in combination: a track divided into track circuit sections; a semaphore; two circuit controllers; a circuit for governing said semaphore including in series said two circuit controllers, one of said circuit controllers being governed by a predetermined portion 10 of the track and being open when that portion of the track is occupied by a train; a translating device for closing the other circuit controller when energized; another semaphore for governing traffic in the same 15 direction as the first semaphore and protecting a portion of the track in advance of the first mentioned portion; a third circuit controller operated by said another semaphore. said third circuit controller being closed 20 when said another semaphore indicates that the portion of track protected thereby is not occupied by a train, and being opened when said another semaphore indicates that said portion of the track is occupied; a fourth 25 circuit controller governed by said first mentioned portion of the track and closed when that portion is occupied; an energizing circuit for said translating device including in series said third and said fourth circuit controllers only; a maintaining circuit including a source of current for maintaining said translating device energized, which circuit is effective only when said energizing circuit is closed at the time the maintaining circuit 30 is closed; and a fifth circuit controller for controlling said maintaining circuit, said fifth circuit controller being closed while 35 said second mentioned portion of the track is occupied.
21. In a signal system for railways, in combination: a track divided into track circuit sections and each having a track relay; a first semaphore and a second semaphore for governing traffic in the same direction over the track; two circuit controllers; a circuit for governing the first semaphore including in series both of said circuit controllers, one of said circuit controllers being actuated by the track relay of a predetermined track section and being opened when 40 that track section is occupied; a translating device, which, when energized, closes the other circuit controllers; a third circuit controller operated by the second semaphore and closed when a portion of the track in 45 advance of the first mentioned track section is not occupied and being opened when that portion is occupied; a fourth circuit controller actuated by the track relay of said predetermined track circuit and closed when 50 that track relay is deenergized; an energizing circuit for said translating device including in series said third and said fourth circuit controllers; a maintaining circuit including a source of current for maintaining 55 said translating device energized, which circuit is effective only in case said energizing circuit is closed at the time the maintaining circuit is closed; and a fifth circuit controller for controlling said maintaining circuit 60 which is closed so long as the second mentioned portion of the track is occupied.
